Inventor
William A. Zeidler,

John J. Sheetz

Attorney

UNITED STATES PATENT OFFICE.

WILLIAM A. ZEIDLER, OF NEW YORK, N. Y.

IRONING MACHINE.

Application filed January 5, 1921. Serial No. 435,211.

To all whom it may concern:

Be it known that I, WILLIAM A. ZEIDLER, a citizen of the United States, residing at New York, in the county of Bronx and State 5 of New York, have invented certain new and useful Improvements in Ironing Machines, of which the following is a specification.

This invention relates to improvements in ironing machines and the like, and has 10 for its primary object to provide a simple and effective means for applying pressure to the feed rolls during the ironing operation, and for quickly releasing and raising them from the work; the same means being 15 adapted to lock said rolls in position during the operation.

Another object of the invention is to provide an improved means of mounting and heating a mangle roll. A further object is 20 to provide novel means to supply heated air from the interior of the roll to the burner. A still further object is to give an improvement in relation to the feed table, heated roll, and padded drums, whereby finely finished work will be quickly produced. 25

With these and other objects in view, the invention resides in the structure, combination and arrangement of parts as will be hereinafter more fully set forth in the accompanying specification and drawings, in 30 which—

Figure 1 represents a side elevation of a machine embodying my invention,

Figure 2 is a fragmentary top view partly 35 in section of cylinder mounting and heating means,

Figure 3 is an enlarged side elevation of the rock shaft and pressure arm, with a tension rod and spring in place,

Figure 4 is a top plan view of the machine 40 with the rolls broken away in order to show the operating pedals, etc.,

Figure 5 is an enlarged side elevation of the rolls with one side of the frame and connections removed.

Figure 6 is an enlarged detail sectional view of the control pedal,

Figure 7 is a detail perspective of the chimney.

In the embodiment of my invention, herein 50 illustrated, 1—1 represent legs located at each end of the machine, and 1^a, 1^a, represent cross bars, upon which is journalled a rotary shoe or drum 2. A feed shelf 3 is provided 55 at the front, formed preferably of wood, and having an overhanging lip 3^a of metal,

closely approaching but not touching the drum 2. The drum is a hollow cylinder having spiders 2^a at the ends fixed upon a foraminous hollow shaft 4 which serves as a 60 combined journal and burner. The shaft projects beyond the drum at each end and is there supported upon roller bearings 4^a moving in a suitable raceway 4^b, on bars 1^a of the frame. The foramina of the shaft 65 are within the drum only. The shaft is open at the left end, and the raceway there is closed at the outer side by a cap plate 5 spaced from the end of the shaft suitably to admit air entering through the bearing. 70 In the cap plate a nozzle 6 is provided arranged to direct gas axially into the shaft. A fuel conduit 6^a leads to the nozzle. The jet from the nozzle serves to draw air into the burner through the bearing, keeping 75 the latter cool, and forming a properly combustible mixture.

Pivots mounted upon brackets 7—7 located, one upon each side of the top of the machine at the rear, are jointed arms, each of which comprises two links, 8 and 9, respectively. Two cloth covered rolls, 10 and 11, respectively, are journaled between these arms, the centrally disposed shaft 10^a of the roller 10 pivotally connecting the ends of the links 8 and 9, while the shaft 11^a of the roller 11 is journaled between the free ends of the links 9—9 at either side of the machine.

Rotatably mounted upon a stud 7^a, of the bracket 7 at the left side of the machine, there is a worm gear 12 meshing with a worm 13, mounted upon a shaft 14, which is journaled within the member 15 as shown. A grooved pulley 16 is mounted upon the 90 outer end of the shaft 14, and is connected by a belt 17 to the pulley 18^a of an electric motor 18. A drive wheel 19 here shown as of the sprocket type is centrally mounted upon the face of the worm gear 12, and is connected by a chain 20 to a larger sprocket wheel 21 mounted upon the left end of the shaft 11^a of the roller 11. Upon the right ends of the shafts 10^a and 11^a of the rollers 10 and 11, are mounted sprocket wheels 22 and 23 respectively, which are connected with a sprocket chain as shown. It follows that the motor driving pulley 16 will impart motion to the roller 11 through the sprocket chain 20, and thence to the roller 10 through the sprocket chain 24 connecting the 95 100 105 110 sprocket wheels 22 and 23.

It will be seen that the compound arms carrying the rolls 10 and 11, may be flexed due to the pivotally connected links 8 and 9, and in order to limit this movement, each link 8 is formed with a squared projection 8^a at the head, while the links 9 are formed with a lug or stop 9^a upon the inner side as shown in Figure 4. The projection 8^a and the lug 9^a are in close proximity, so that the upward movement of the link 9 relative to the link 8 is limited.

A longitudinal shaft 25, journaled within the lower cross braces 1^a—1^a at each side of the machine, carries permanently affixed 15 crank arms 26—26, at each end, and each of these arms is provided with a pivotally mounted wrist member 26^a, through which a rod 27 freely passes. The rods 27 are pivotally connected at their upper ends with the 20 links 9—9, at a point midway between the rolls 10 and 11, and their lower ends, beyond the member 26^a, are each provided with a nut 27^a and a jam-nut 27^b. A coiled spring 28 is disposed upon the rod 27 between the 25 nut 27^a and the member 26^a, forming a yielding means for transmitting pressure from the wrist to the rod. A nut 27^c is located upon the rod 27, above the wrist by which a positive lift is provided. Lugs 1^b formed 30 integral with the cross braces 1^a, on each side of the machine serve as stops for the crank arms after they pass the lower dead center in lowering movement, lowering the rolls 10 and 11. Due to the spring 28 they 35 become yieldingly locking on the ironing bed.

Two crank arms 29 and 30 respectively, are fixed upon the shaft 25, midway of the machine, extending in opposite directions. 40 The crank 29 is connected with a pedal lever 31 by a link 32, and the crank 30 is connected with another pedal lever 33 by a link 34. The lever 33 is of channel iron with its bight portion at the upper side. The lever 33 has 45 pivoted therein an upstanding forwardly leaning latch 35 notched at the upper front part 36 to receive the upper rearwardly turned flange of a channel bar cross brace 34 between the two front legs of the frame. 50 The latch has slidably thereon a release member 40 having an inclined part 41 which on upward movement will engage the lower flange of the bar 34 and ward the latch rearwardly until the notch 36 is clear of the 55 upper flange. This action is effected by pressing a button 42 close to the foot plate 33^a on the pedal lever 33.

The latch release comprises a strap of metal having its upper end bent at right 60 angles to its major part and apertured to slidably receive the latch. Immediately below the apertured part it is bent forwardly and then rearwardly at oblique angles to form a V-shaped part 43, the upper side of 65 which may wipe against the flange when the

release is moved upward. From this inclined part the strip is extended downward through the lever 33, which is suitably apertured to hold its lower part slidably. The lower end 44 of the strip is recurved forwardly and apertured to receive the rear end of a small lever 45 between the sides of the lever 33, the outer end of the lever being closely adjacent the pedal plate 33^a and attached to the stem of the button 42. If desired a spring 46 may be employed to bear the latch into operative position.

A shelf 37 is disposed between the standards 1—1, at a point below the drum 2 in order to receive articles from the ironing rolls, and the shelf 37 is provided with a hinged extension 37^a. An electric switch 38 is provided at the left of the frame having an actuating lever 38^a connected with a member 39 upon the adjacent rod 27, so that when the rolls 10 and 11 are raised the switch 38 will be opened, stopping the motor, but when the rolls are lowered to the ironing position as shown in the drawings, the switch 38 will be automatically closed and the motor will be started.

In operation, the rolls 10 and 11 are first released by the pedal 33, and the article to be ironed is next placed upon the shelf 37 and extended to the roll 2. The rolls 10 and 11 are then lowered to the ironing position by foot pressure applied to the pedal 31 acting on the rod 32, crank 29, shaft 25, cranks 26, spring 28, and rods 27 connecting with the links 9—9 of the articulated arms carrying the rolls, the switch 38 having been closed by the downward movement of the rod 27. The rolls 10 and 11 are thereby held yieldingly pressing upon the work, pressure in both rolls being equalized. Full stroke of the pedal 31 carries the wrist 26^a beyond the dead center and the rolls are locked in ironing position without further effort by the operator.

The article after ironing passes backwardly over the roll 2 and falls to the shelf 37.

The rolls 10 and 11 are raised by foot pressure applied to the pedal 33 acting on the rod 34 the crank 30, shaft 25, cranks 26 and rods 27 connecting with the links 9—9 of the articulated arms carrying the rolls. As the pedal 33 is depressed, raising the rolls, the notch 35^a of the latch member 35 engages the flange 1^a, holding the rolls in the raised position, the switch 38 being at the same time opened by the rod 27. When it is desired to lower the rolls, a quick downward thrust upon the pedal 33 is sufficient to disengage the latch member 35, or the pedal may be depressed slightly and the latch member disengaged by the toe or other means.

I claim:

1. In a domestic ironing machine, a frame,

- a horizontal cylindrical heated drum journaled therein, a pair of parallel horizontal rolls of smaller diameter than said drum and located above the same, connecting links 5 at each end of said rolls to which both rolls are journaled, other links pivoted to said frame and to said first links, means for driving said rolls, and operating means connected to said first links for raising and lowering the same.
2. In a domestic ironing machine, a frame, a horizontal cylindrical heated drum journaled therein, a pair of links pivoted to opposite ends of said frame, a second link 15 articulated to the end of each of said first links, a pair of parallel horizontal rolls journaled in said links and located above the drum, means for driving said rolls, and operating rods pivotally attached to said links 20 at a point between said rolls whereby said rolls may be raised and lowered.
3. In an ironing machine, a frame, a horizontal, cylindrical heated drum mounted thereon, a horizontal feed shelf at one side 25 of said drum, a pair of arms pivoted to the frame at the opposite side of said drum, other arms pivoted to the ends of said first arms, a pair of parallel horizontal rolls pivoted between the respective ends of said 30 last arms, said rolls being of smaller diameter than said drum and located above the same and the top of said shelf being substantially level with the line of contact between the nearest roll and drum, and means 35 for raising and lowering said last arms, and means operative after said arms are lowered for increasing the downward force thereon.
4. In a domestic ironing machine, a frame, a horizontal cylindrical heated drum journaled therein, a pair of links pivoted one at 40 each end of said frame at a point above and at one side of said drum, a second link pivoted to the free end of each of said first links, a pair of parallel horizontal rolls of 45 smaller diameter than said drums and located above the same, the ends of said rolls being journaled in said last mentioned links, means for driving both of said rolls in the same direction, operating rods articulated 50 to said last named links at a point between said rolls, and means for raising and lowering said rods so as either to elevate said rolls away from said drum or to draw them against the drum with a force which is divided between said rolls.
5. In a domestic ironing machine, a frame, a horizontal cylindrical heated drum journaled therein, a pair of parallel horizontal rolls of smaller diameter than said drum and located above the same, connecting links 60 raising the roll upon a downward movement of one of the pedals and for permitting a downward movement of the roll upon an upward movement of the pedal, said means comprising mechanism for increasing 65 the pressure upon the roll upon a downward movement of another of the pedals.
6. In a domestic ironing machine, a frame, a horizontal cylindrical heated drum journaled therein, a drive wheel journaled to 70 said frame with its axis parallel to said drum, a pair of links pivoted one to each end of said frame co-axial with said drive wheel, other links pivoted to said first links, a pair of parallel horizontal rolls journaled 75 to said last links, driving connections between one of said rolls and said drive wheel, other driving connections between said rolls and means for raising and lowering said 80 links.
7. In a domestic ironing machine, a frame, a horizontal cylindrical heated drum journaled thereto, a drive wheel journaled to said frame upon an axis parallel to said drum, a pair of links pivoted one to each 85 end of said frame co-axial with said drive wheel, other links pivoted to said first links, ironing rolls journaled to said last links and co-operating with said drum, operating rods connected to said last links between said 90 rolls to raise and lower the same, means connecting said drive wheel to said rolls in driving relation, a worm gear for operating said drive wheel and an electric motor carried by said frame operatively connected 95 to said worm gear.
8. In an ironing machine, in combination, a frame, a heated member, and an ironing roll co-operating with said heated member, a rock shaft journaled in said frame beneath 100 said heated member and having an arm at each end, an eye pivoted to the free end of each arm, an operating rod sleeved in each of said eyes and having its upper end operatively connected to said ironing roll, a 105 pair of spaced stops on said rod, one above and one below said eye, a compression spring interposed between said eye and the lower stop, and means to rotate said rock shaft in both directions and to hold it at different 110 set positions.

In testimony whereof I affix my signature.

WILLIAM A. ZEIDLER.
